UNITED STATES PATENT OFFICE

SAUL C. APPEL, OF MEDFORD, MASSACHUSETTS

COMBINED ANCHOR AND PIPE SLEEVE

Application filed December 18, 1928. Serial No. 326,858.

My present invention relates to piping devices and more particularly to a combined anchor and pipe sleeve.

In the construction of a modern type of building, particularly those with concrete floors, a large item of the cost of installing the piping is that of preparing suitable passages for the risers and for the means of anchoring such risers at appropriate points in the building. It has been customary to place a sleeve in position prior to the pouring of the concrete floors and thus have such sleeve in permanent position after the cement has set. It has been customary to use clamps or similar devices as anchors for the risers and also sleeves as a portion of the device for anchoring the risers at appropriate points throughout the building, but to do this it is necessary to cut away on the top of a floor and sometimes on the bottom of a floor or the ceiling of a room below a portion of the concrete floor in order to install or conceal a satisfactory anchor. The cost of this work materially adds to the cost of the construction of the building and is at best but a makeshift. Further, where the anchor is buried in the floor it is practically impossible to remove the pipe for repairs or replacement.

In my present invention I have obviated the objections of prior constructions and have devised an improved combination anchor and sleeve which may be installed in permanent position during the erection of the building and the pouring of the concrete floors therein, and which may be used as a straight sleeve or as a means for anchoring a riser in position at any desired point in the building or both. In carrying out my invention I provide a centrally arranged cylindrical portion provided with laterally extending wings thereon and which may be firmly anchored within the concrete forming the floor of the building. This element is preferably located intermediate the upper and lower faces of the floor, and screwed into the top and into the bottom, should it be desirable, is a section of pipe, thus forming a through passage or sleeve in the floor. Secured to the lower end of the cylindrical element so as to be removable from the lower face of the floor is

an element in the shape of a collar, which acts as a cover for the housing, within which may be housed a coupling connecting two lengths of pipe forming elements of the system of pipe in the building, and such coupling together with the cylindrical portion anchored within the cement floor acts as an anchor for the pipe forming part of the system of pipe. Where the device is to be used in connection with furred or dropped ceilings in concrete floor construction, I preferably secure to the ceiling a short length of pipe extending downward through the furred or dropped ceiling. With my improved device, I am able to readily and easily remove the piping for repair or replacement.

The object of my invention, therefore, is an improved combination anchor and pipe sleeve.

In the accompanying drawings—

Fig. 1 designates a side elevation of my improved anchor and pipe sleeve shown in position in a section of concrete floor;

Fig. 2 is a longitudinal section of Fig. 1;

Fig. 3 is a sectional bottom plan on the line 3—3 of Fig. 1 with the concrete flooring removed, and

Fig. 4 is a side elevation, partly in section of a modification.

Referring to the drawings, 10 designates a cylindrical member having formed integral therewith and diametrically arranged with respect to each other laterally extending wings or plates 11, such wings or plates 11 being of any suitable dimensions. The cylindrical member 10 is counterbored at one end, as indicated at 12, such counterbored portion being of a suitable diameter and depth to receive a coupling 13 forming part of a piping system. Also, the cylindrical member 10 is counterbored at the other end, such counterbored portion being of suitable depth and tapped, as indicated at 14, to receive the threaded end of a section of pipe 15. The depth of the counterbored portions is such as to leave an intermediately located wall 16 in the cylindrical member 10, which is drilled at 17 to receive as a loose sliding fit a pipe 18 forming part of the piping system of the building, and this piping 18 is threaded into 100

one end of the coupling 13. The material of the cylindrical member 10 on the lower face thereof is drilled and tapped to receive the threaded end of cap screws 19, which cap screws are utilized to hold a collar 20 in position on the lower face of the cylindrical member 10. This collar 20 is drilled at 21 to allow a pipe 22 to pass through as a loose sliding fit and which pipe 22 screws into the lower end of the coupling 13 and forms part of the piping system of the building. The sleeve above described and as illustrated in Figs. 1, 2 and 3, is adapted to be embedded in the concrete floor 23 during the pouring of such floor and in which event naturally the sections of pipes 18 and 22, as well as the coupling 13, are not present. In such event also it will be obvious that the section of pipe 15 of suitable length, depending on the thickness of the flooring 23, will be screwed into the threads 14, and I find it preferable to have such section of pipe 15 extend for a slight distance above the finished surface of the floor, as clearly shown in Figs. 1 and 2. It is desirable to have, from a finished standpoint, the lower face of the collar 20 substantially flush with the lower face of the floor 23 and in order that this may be done, I find it preferable to, during the process of construction, substitute for the cap screws 19, other screws somewhat similar but of a length to pass through the usual mould board employed in casting the floor 23. That is, the mould board is put in position with the holes registering with the holes in the collar 20 and the long cap screws pass through the holes in the mould board and through the holes in the collar 20 and then into the tapped holes in the body of the cylindrical member 10. It will be obvious therefore that the mould board employed has secured thereto not only a collar 20 but also the cylindrical member 10 that carries the section of pipe 15 and that the mould board, being fixed in position as regards the floor, that the cylindrical member 10, together with the attachments thereon, is also similarly fixed in position. After the floor 23 has been cast and has had time to set, the mould boards employed are naturally removed and therefore the long cap screws employed are removed and the cap screws 19 shown in Figs. 1, 2 and 3, are substituted therefor and the device is now in fixed position within the floor 23.

When used as a sleeve and not as an anchor, the pipe 18 or 22, or a similar pipe is passed through the openings 21 and 17 and the construction, therefore, is merely a sleeve. Should it be desired, however, to utilize the construction as an anchor, the cap screws 19 are removed, the collar 20 also removed and a coupling 13 placed in the counterbored portion 12, after which the collar 20 is replaced, as are also the cap screws 19, and the device 18 and 22 are screwed into the upper and low-

er face of the couplings 13 respectively. The device, therefore, becomes a combined anchor and sleeve and it will be obvious that the pipes 18 and 22 are securely anchored at the cylindrical member 10 shown in the drawings and expansion takes place, therefore, in such pipes upward and downward respectively from the cylindrical member 10.

My improved device acts as a support for a vertical pipe, obviating the necessity of putting in a pipe hanger or support. Further, it may be used in the horizontal position and acts in this position as a support, and as an anchor.

In Fig. 4, there is shown a modification of my device employed where a furred or dropped ceiling is utilized, such furred or dropped ceiling being indicated by the reference numeral 24. The construction of this modification is identical with that shown in Figs. 1, 2 and 3, except that the lower surface of the collar 20 is threaded, as indicated at 25, to receive the upper threaded end of a section of pipe 26 that is long enough to extend downward and through for a suitable distance beyond the lower face of the furred or dropped ceiling 24.

Having thus described my invention, what I claim as new is:

1. In a device of the kind described, the combination of a cylindrical member, laterally extending anchoring plates formed integral therewith, a section of pipe secured to one end of said cylindrical member, a chamber formed in said cylindrical member, a closure for said chamber and aligned passageways in the cylindrical member and chamber permitting passage of a pipe therethrough.

2. In a device of the kind described, the combination of a cylindrical member, anchor plates extending laterally outward therefrom and formed integral therewith, a section of pipe secured to one end of said cylindrical member, a chamber formed in the cylindrical member at the end remote from said section of pipe, a closure for said chamber, said chamber permitting the insertion therein of a coupling and said coupling being retained therein by the chamber closure and aligned passageways in the cylindrical member and in the closure permitting the passage therethrough of sections of pipe to be engaged by the coupling.

In testimony whereof, I have signed my name to this specification.
